UNITED STATES PATENT OFFICE

169,947

CLOCK

Joseph F. Punzak, Brooklyn, N. Y., assignor to
United Metal Goods Manufacturing Co., Inc.,
Brooklyn, N. Y., a corporation of New York

Application July 26, 1951, Serial No. 16,030

Term of patent 14 years

(Cl. D42—7)

To all whom it may concern:

Be it known that I, Joseph F. Punzak, a citizen of the United States of America and a resident of 7401 Sixth Avenue, Brooklyn, New York, have invented a new, original, and ornamental Design for a Clock, of which the following is a specification, reference being had to the accompanying drawing, forming part hereof.

Fig. 1 is a front view slightly in perspective of a clock showing my new design, and

Fig. 2 is a side perspective view thereof.

I claim:

The ornamental design for a clock, substantially as shown.

JOSEPH F. PUNZAK.
